UNITED STATES PATENT OFFICE.

HOWARD I. WOOD, OF SCHENECTADY, NEW YORK, ASSIGNOR TO GENERAL ELECTRIC COMPANY, A CORPORATION OF NEW YORK.

INCANDESCENT ELECTRIC LAMP.

No. 819,624.

Specification of Letters Patent.

Patented May 1, 1906.

Application filed October 31, 1904. Serial No. 230,725.

To all whom it may concern:

Be it known that I, HOWARD I. WOOD, a citizen of the United States, residing at Schenectady, county of Schenectady, State of New York, have invented certain new and useful Improvements in Incandescent Electric Lamps, of which the following is a specification.

The invention herein described relates to incandescent electric lamps or similar apparatus, and more especially to the means whereby current is conveyed through the walls of the glass bulb or envelop. Instead of securing the vacuum-tight joint by metal, such as platinum, having substantially the same coefficient of expansion as glass, I make use of a ring or similar device of copper, iron, or other suitable metal shrunk tightly about a portion of the glass envelop and forming therewith a perfectly vacuum-tight joint. Electrical connection is made with such a ring by means of a wire or conductor passing through the glass and engaging said ring.

The novel features which characterize my invention I have pointed out with particularity in the appended claims.

The invention itself, however, will be better understood by reference to the following description, taken in connection with the accompanying drawings, in which—

Figure 1 is a perspective view of an incandescent lamp embodying my invention. Fig. 2 is a modification; and Fig. 3, a sectional view of a portion of Fig. 2.

Referring to the drawings, more especially to Fig. 1, the part numbered 1 represents the glass bulb of an incandescent lamp. The lower portion of this bulb may be of tubular form, as at 2. Internal current-conveying conductors which support the usual filament 3 are indicated at 4 and 5. The upper ends of these conductors are held in fixed relation to each other by a ball or mass of glass 6, fused about them. The lower ends of the conductors are passed through the walls of the tube 2 at 7 and 8 and are bent around for a short distance in contact with the outer wall of the tube, as at 9 and 10, respectively. The openings 7 and 8 may be such that the conductors 4 and 5 pass loosely therethrough or the walls of the openings may, if desired, be sealed about the conductors. In either case, however, the joint of itself is unavoidably leaky. In order to secure a tight joint,

I seal about the tubular portion 2 a pair of 55 rings 11 and 12, one of which is shrunk about the tubular portion so as to engage the end 9 of the conductor 4 and the other so as to engage the end 10 of the conductor 5. These rings or bands are preferably of metal having 60 a higher coefficient of expansion than that of glass and may be formed conveniently of copper, iron, suitable alloys, or the like. They are of such diameter that they may be easily passed over the tubular portion 2 to 65 the position desired. After the rings are placed in position, either one at a time or both together, the parts are then heated in the ordinary glass-blowers' gas-jets to a temperature, such as a red heat, at which the glass 70 becomes soft. Air-pressure is then exerted to force the glass into intimate contact with the metal rings or bands. When this has been accomplished, the parts are allowed to cool.

When cool, the metal bands, having a larger coefficient of expansion than the glass, necessarily contract faster, and thus shrink tightly about the glass and form an exceedingly tight joint. The entrance of air into 80 the lamp-bulb through the passages afforded by the openings 7 and 8 is thus effectually prevented.

In order that the glass may not be cracked or sheared by the force of contraction of the 85 metal bands, it is necessary that the metal be thin enough to stretch in response to the resistance to compression afforded by the glass. A thickness of metal of about one one-hundredth of an inch will be found satisfactory for this purpose, though of course this may vary somewhat, dependent upon the thickness and shape of the glass portion about which the bands are placed.

Instead of employing two bands or rings I 95 may, as shown in Fig. 2, utilize but a single band and effect the desired connections, as shown in this figure.

The tubular portion of the incandescent-lamp bulb is indicated at 12. The filament-carrying conductors 13 and 14 pass through the walls of the bulb, as at 15 and 16, and are bent around on the outside, as indicated at 17 and 18. A plate of metal 19 is placed over the conductor end 18, so as to make 105 contact therewith. A sheet of mica 20 is placed over this metal plate, and then around all is mounted a ring or band 21, of metal, a

portion of which contracts with the conductor end 17 of the conductor 14. The parts are then heated, as before, and the glass blown into intimate contact with the metal parts which are in juxtaposition therewith. Upon cooling, the metal band 21, which as in the similar construction in Fig. 1 is thin, contracts yieldingly about the glass and forms a perfect joint therewith, so as to prevent the entrance of air about the points 15 and 16, where the conductors 13 and 14 pass through the glass tube 2.

Electrical connection to the conductor 14 is made with the ring or band 21 and for the other conductor 13 with a lead 22, connected to plate 19. As already indicated, this plate 19 while making electrical connection with the conductor end 18 is insulated from the metal band 21 by the plate 20, of mica, asbestos, or other suitable refractory insulating material.

What I claim as new, and desire to secure by Letters Patent of the United States, is—

1. The combination of a vitreous envelop, a thin metal band shrunk, while the parts are hot, about a portion of the envelop so as

to make intimate contact therewith, and a metal conductor or wire passing through the envelop from the inside and making contact with the band or ring on the outside. 30

2. The combination of a vitreous envelop, conductors passing through the walls of said envelop from the inside, and external connections for said conductors formed in the case of one conductor of a metal plate or sheet and in the case of the other conductor of a sleeve or band, said plate or sheet and said sleeve or band both forming vacuum-tight joints with the envelop. 35

3. A seal for incandescent lamps, which 40 consists of a sleeve or band of thin metal in intimate contact with the glass portion of the lamp, and a conductor passing through the glass and engaging the inner side of said band or sleeve. 45

In witness whereof I have hereunto set my hand this 29th day of October, 1904.

HOWARD I. WOOD.
